UNITED STATES PATENT OFFICE.

WILLIAM G. HULLHORST, OF TOLEDO, OHIO, ASSIGNOR TO THE RANSOM & RANDOLPH COMPANY, OF SAME PLACE.

DESIGN FOR A DENTAL CABINET.

SPECIFICATION forming part of Design No. 29,996, dated January 10, 1899.

Application filed September 25, 1897. Serial No. 653,056. Term of patent 14 years.

To all whom it may concern:

Be it known that I, WILLIAM G. HULLHORST, a citizen of the United States, residing at Toledo, Lucas county, Ohio, have invented and produced a new and original Design for Dental Cabinets, of which the following is a specification, reference being had to the accompanying drawing, made part hereof.

The figure is a perspective view of my cabinet entire.

In the drawing is represented a dentist's cabinet, consisting of two vertical rows of compartments arranged side by side, one row of compartments being smaller than the other and designed for holding the smaller and more compact articles—tools, supplies, and the like—required by a dentist in the practice of his profession.

a and *b* are compartments for doors arranged to be raised and slipped horizontally into pockets provided for that purpose.

c c c are drawers, and *d* is a compartment having a door which is hinged at its lower horizontal margin.

The compartments and drawers above referred to form one of the vertical rows above alluded to.

e is a tray-compartment having a glass door *f*, curved or formed as the segment of a cylinder. Through this glass door is disclosed a 30 series of extensible trays *k*, symmetrically arranged and supported one above the other.

l l are drawers beneath the tray-compartment. *m* is a shelf beneath said last-mentioned drawers, and *n* is another shelf near 35 the floor, extending the whole width of the cabinet. The top of the tray-compartment also serves as another shelf.

As will be seen, the material features of my design consist of the two vertical series of 40 compartments and drawers disposed side by side, one of the series including the symmetrical arrangement of the extensible trays and their supports within a compartment provided with a segmental or arc door. 45

Having described my invention, what I claim as new, and desire to secure by Letters Patent, is—

The design for a dental cabinet as herein shown and described.

WILLIAM G. HULLHORST.

In presence of—

ORAH A. MCMILLAN,
F. G. CRANDELL.
